[57] CLAIM

The ornamental design for an infant nurser or similar article, as shown.

DESCRIPTION

FIG. 1 is a perspective view of the infant nurser or similar article, showing our new design;
FIG. 2 is a front elevational view thereof;
FIG. 3 is an end elevational view thereof;
FIG. 4 is a left side elevational view thereof;
FIG. 5 is a rear elevational view thereof; and
FIG. 6 is an elevational view of the end opposite that shown in FIG. 1 thereof.
